UNITED STATES PATENT OFFICE

148,211

DESIGN FOR A ROTARY TOOL CHUCK HEAD OR SIMILAR ARTICLE

Alfred A. Bamberger, Flushing, N. Y., assignor to
Speedo Manufacturing Co., Inc., New York,
N. Y.

Application June 20, 1946, Serial No. 130,893

Term of patent 14 years

(Cl. D54—13)

To all whom it may concern:

Be it known that I, Alfred A. Bamberger, a citizen of United States, residing at Flushing, in the county of Queens and State of New York, have invented a new, original, and ornamental Design for a Rotary Tool Chuck Head or Similar Article, of which the following is a specification, reference being had to the accompanying drawing, forming part thereof.

In the drawing:

Fig. 1 is a side view of a rotary tool chuck head showing my new design; and

Fig. 2 is a bottom plan view thereof.

I claim:

The ornamental design for a rotary tool chuck head or similar article, as shown.

ALFRED A. BAMBERGER.
